UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

ENVELOP-MACHINE.

1,285,839.

Specification of Letters Patent. Patented Nov. 26, 1918.

Application filed February 12, 1916. Serial No. 78,025.

To all whom it may concern:

Be it known that I, WILLARD E. SWIFT, a citizen of the United States, residing at Worcester, in the county of Worcester and 5 Commonwealth of Massachusetts, have invented a new and useful Improvement in Envelop-Machines, of which the following is a specification, accompanied by drawings forming a part of the same.

10 My present invention relates particularly to improvements in envelop machines designed for the manufacture of what are known as window envelopes, or envelopes having an opening in their face covered by a 15 transparent patch, through which an address upon an inclosure may be read, and my present invention has to do with mechanism for applying the transparent patch to cover the opening formed in the envelop 20 blank, said mechanism being applied to and forming the component part of an envelop machine for gumming the flaps of the envelop blank and folding the blank to form the completed envelop. In the accompanying 25 drawings I have shown so much of an envelop machine as is necessary to illustrate the construction and operation of the patch applying mechanism, and its adaptation to an envelop making machine.

30 Figure 1 represents a side view of an envelop machine.

Fig. 2 is a plan view.

Fig. 3 is a transverse sectional view on the plane of the broken line 3-3, Fig. 2, 35 and showing upon a larger scale the patch applying mechanism.

Fig. 4 is a plan view of the patch applying mechanism shown upon the same scale as in Fig. 3.

40 Similar reference characters refer to similar parts in the different figures.

The mechanism for gumming the envelop blanks and for folding the blanks to form a completed envelop, are substantially the 45 same as shown in the patent to William D. Slater, No. 893,105, issued July 14, 1908; both the gumming and flap folding mechanisms being of a well known type in common use, a brief description will be sufficient.

In the accompanying drawings 1 represents the framework of the machine, 2 a feeding table upon which a pile of envelop blanks 3 is supported, said blanks having 55 openings therein in proper position to dis-

close the address upon an inclosure contained in the envelope. 4 is a vertically reciprocating spindle carrying dies 5 and 6 for gumming the seal and back flaps of the blank. Gum is applied to the under side 60 of the gumming dies 5 and 6 from a gum box 8 by a traversing gumming roller 9, in the usual manner.

The gummed blanks are transferred from the pile 3 to a position upon a creasing table 65 10 beneath a vertically reciprocating plunger 11 which by its downward movement forces the blank through an opening in the creasing table 10 upon a folding bed where the flaps are folded by hinged folders 12, 12. 70 The transfer of the blank from the pile 3 to the folding mechanism is accomplished by a reciprocating carriage 13 by which a period of dwell is given to the blank between the gumming and folding mechanisms when 75 the blank is directly over the pressing table 14. The construction and operation of the blank transferring mechanism and pressing table are the same as that described in the aforesaid patent to William D. Slater. During the period of dwell of the blank upon the pressing table 14 it is registered in proper 80 position relatively to a patch applying mechanism by means of registering pins 15, Fig. 3. The mechanism for actuating the registering pins 15 is not herein shown or described in detail as it is the same as that described in the aforesaid patent to Slater and forms no part of my present invention. 85

While the blank is being held in proper 90 position upon the pressing table 14 I apply a transparent patch to cover the opening in the blank by mechanism which forms the subject of my present invention, and which is shown upon a larger scale in Figs. 3 and 95 4 of the accompanying drawings.

Located at one side of the pressing table 14 is a patch holder 16, consisting of a rectangular box open at the top and bottom. At the lower end the patch holder is provided with inwardly projecting toes 17, 17, 100 which overlap the edges of the lowermost patch in the pile of patches 18 held in the patch holder. Pressing upon the pile of patches is a follower 19 attached to the lower 105 end of a spindle 20. The follower 19 is pressed down upon the patches by means of a spiral spring 21, interposed between the follower and a frame 22. Immediately beneath the patch holder 16 is a gum box 110

23 containing gum 24 in which is immersed a gumming die 25, mounted upon a vertically reciprocating spindle 26 and actuated by a cam 27 on one of the driving shafts 5 28 of the machine. The gumming die 25 is shaped in conformity with the opening in the envelop blank and is adapted by the vertical movement of the spindle 26 to apply a narrow strip of gum upon the under side 10 of the lowermost patch held in the patch holder 16.

Attached to the fixed framework of the machine is a narrow bar 29 which extends lengthwise and immediately beneath the patch holder 16. The gumming die 25 is notched at each of its ends to receive the bar 29 and allow the face of the die 25 to come into contact with the lowermost patch. The bar 29 prevents the patch from following the die 25 as the latter descends. The patch holder is provided on opposite sides with projections 30 which slide in grooves 31 in the parallel rails 32. The rails 32 are tied together at one end by a cross-piece 33 and at the opposite end they are attached to a hub 34 which is journaled upon a stud 35 held in a bracket 36 projecting from the framework of the machine.

The patch holder 16 supports, by means 30 of lugs 37 and bolts 38, a frame 22, from one end of which extends a rack bar 40 engaged by a gear 41 journaled on the stud 35. Attached to the gear 41 is a pinion 42 which is engaged by a rack bar 43. At the 35 proper period a reciprocating motion is given to the rack bar 43 by means of a cam 44 on the shaft 28, and a spring 45. By the action of the cam 44 and spring 45 the gear 41 is oscillated, thereby imparting a 40 reciprocating motion to the rack 40. The movement of the rack 40 gives a back and forth motion to the patch holder 16 in the rails 32, moving the patch holder from its position shown in Fig. 3 over the gum box 45 23 to a position directly over the pressing table 14, thereby bringing the patches in registration with the envelop blanks as they are brought to rest upon the pressing table.

When the patch holder has been moved 50 from the position shown in Fig. 3 to a position directly over the pressing table 14, a rocking motion is given to the rails 32 on the stud 35 by means of an arm 46 projecting from the hub 34 and pivotally connected 55 by a link 47 with an actuating cam, not shown. The rocking motion of the rails 32 lower the patch holder until the lowermost patch contained therein is brought into contact with the envelop blank resting on the 60 table 14. As the rocking motion of the rails 32 is reversed into the position shown in Fig. 3, the lowermost patch with gum applied to its under surface is withdrawn 65 by its adhesion to the envelop blank out of engagement with the toes 17, leaving the

lowermost patch attached to the envelop blank as the patch holder rises. The reciprocating motion of the rack bar 43 then oscillates the gear 41 to return the patch holder to its original position over the gum 70 box 23.

The patched blank is then carried forward by the hooks upon the reciprocating carriage 13 to its position on the creasing table 10. 75

The operation of the machine is as follows:—The envelop blanks in the pile 3 are successively gummed by the flap gumming dies 5 and 6 and transferred from the pile 3 to a position on the table 14, by means of 80 the carriage 13 in the usual and well known manner. At the next reciprocating motion of the carriage another blank is carried forward from the pile 3 and the blank previously deposited upon the pressing table 14 85 is moved forward upon the creasing table 10. The blanks in the pile 3 are therefore successively gummed and transferred to the pressing table 14 and from the pressing table 14 to the creasing table 10. During 90 the movements of the blanks gum is applied in proper position upon the under side of the lowermost patch by the vertically reciprocating patch gumming die 25, and while the blank remains at rest upon the 95 table 14 the patch holder is moved forward in the rails 32 into proper position over the blank when the rails 32 are depressed carrying the gummed patch into contact with the blank. The patch holder is then raised 100 and moved back into the position shown in Fig. 3 when the operation is again repeated.

The position of the blank on the pressing table 14 is represented at 48, Fig. 4, and the 105 shape of the opening in the blank is shown at 49, Fig. 4. The patch applied to the blank is represented at 50, Fig. 2.

I claim,

1. In an envelop machine, a patch applying mechanism, comprising a pressing table, means for registering an envelop blank having an opening therein on said table, a movable patch holder, means for applying gum to a patch contained in said holder, means 110 for moving the patch holder to bring the patch above and into registration with the opening in the envelop blank on said table, and means for moving the patch holder to carry the gummed patch into contact with 115 the envelop blank.

2. In an envelop machine, a patch applying mechanism comprising a stationary pressing table, means for moving an envelop blank having an opening therein upon 125 said table, means at one side of said table for supporting a patch to cover the opening in the blank, means for registering the blank on said table, means for applying adhesive material to the patch in said supporting 130

means, means for moving the patch in a line transverse to the line of movement of the blank into a position above and in registration with the opening in the blank on said table, and means for bringing the patch and blank into contact.

3. In an envelop machine, a pressing table, means for moving an envelop blank by a horizontal movement on said table, a movable holder for a transparent patch at one side of said table, means for applying adhesive material to a patch in said patch holder, means for moving the patch holder by a movement transversely to the movement of the blank, and means for depressing said patch holder to bring the patch into contact with the blank on said pressing table.

4. In an envelop machine, a stationary pressing table, means for moving a blank upon said table by a horizontal movement, means for registering the blank on the table, a movable patch holder for a stack of patches, with the under surface of the lowermost patch in the stack exposed, means for applying adhesive material to the exposed surface of the lowermost patch in said holder, means for moving the patch holder over the pressing table, and means for depressing the patch holder to carry the gummed patch into contact with the blank on said table.

5. In an envelop machine, means for supporting an envelop blank having an opening therein in a stationary position, a movable holder for a stack of transparent patches, located at one side of said blank support, means for applying gum to the lowermost patch in the stack, a stationary bar beneath the stack of patches to prevent the withdrawal of a patch from the patch holder, means for moving the patch holder off said bar and over the envelop blank on said supporting means, and means for depressing the patch holder to carry a patch into contact with the envelop blank.

6. In an envelop machine, means for supporting an envelop blank, a movable patch holder located at one side of said blank support for holding a stack of patches, a gum box beneath said patch holder, a vertically reciprocating gumming die for transferring gum from said gum box to the lowermost patch in the stack, and means for moving the patch holder to carry the gummed patch into contact with the blank.

7. In an envelop machine, a movable patch holder, horizontal ways for said holder pivotally supported at one end, means for imparting a reciprocating movement to said holder along said ways, and means for gumming a patch in said holder

when said holder is at one end of its movement, and means for rocking said ways on their pivotal support when the patch holder is at the opposite end of its movement.

8. In an envelop machine, means for gumming an envelop blank having an opening therein, means for folding the blank, means for transferring the blank from the gumming to the folding mechanism, with a period of dwell, and means for applying a patch to cover the opening in the blank during its period of dwell, comprising a movable patch holder for holding a stack of patches located at one side of the path of the blank, means for applying gum to the lowermost patch in said holder, and means for moving said patch holder to apply the gummed patch to the blank.

9. In an envelop machine, means for gumming an envelop blank having an opening therein, means for folding the blank, means for transferring the blank from the gumming to the folding mechanism, with a period of dwell, and means for applying a patch to cover the opening in the blank during its period of dwell, comprising a movable patch holder for holding a stack of patches, means for applying gum to the lowermost patch in said patch holder, and means for moving said holder to apply the gummed patch to cover the opening in the blank.

10. In a machine of the class described, a patch applying mechanism for covering the opening in an envelop blank, comprising a movable patch holder for holding a stack of patches, having the under side of the lowermost patch exposed, means for applying gum to the lowermost patch in the stack in said holder, means for retaining the patch during the operation of gumming, and means for moving said patch holder to carry the gummed patch into contact with the envelop blank.

11. In a mechanism for applying a patch to cover an opening in an envelop blank, means for supporting the blank, means for registering the blank on said support, a hollow movable patch holder for holding a stack of patches, a follower inclosed in said patch holder, and means for moving said patch holder from a position at one side of the blank support to a position over said blank support, and means for depressing said patch holder to carry a patch into contact with the blank.

Dated this ninth day of February 1916.

WILLARD E. SWIFT.
